POWER PRESS ECCENTRIC GEAR CAP

Vasil Georgeff, Chicago, Ill., assignor to Danly Machine Specialties, Inc., Chicago, Ill., a corporation of Illinois

Application November 3, 1947, Serial No. 783,747

3 Claims. (Cl. 74—570)

1. My invention relates to power press eccentric gear caps and more particularly to a new and improved construction for an eccentric for a power press which will permit the convenient dismantling of the press in the event of the deformation or bending of the shaft carrying the eccentric gear, as a result of an overload.

In the operation of power presses, it sometimes occurs that two blanks may be placed between the dies instead of a single blank, or that the ram adjustment may become deranged during operation so that the large force exerted at the bottom of the stroke is such that something must yield to relieve it. In some types of power presses the tie-rods will part or elongate. In other types of presses using a solid steel frame, the main shaft around which the eccentric is rotated is bent or deformed between its bearings. When this occurs, the press is frozen and must be dismantled in order to free the deformed shaft. In many cases, it has been necessary to destroy the shaft part in order to dismantle the press. This is not only expensive, but is time-consuming which is of special significance when the power press is part of a production line. The time that the press is incapacitated results in rendering all of the other components of the production line likewise inactive and may represent a considerable economic loss.

One object of my invention is to provide an eccentric gear cap for power presses which may be readily and conveniently dismantled to permit the removal of a bent shaft without time-consuming boring or burning operations, and without destroying press parts.

Another object of my invention is to provide a new and improved power press eccentric gear cap which will enable the ready and convenient removal of a bent or deformed eccentric gear shaft.

A further object of my invention is to provide a power press eccentric gear cap construction in which a bent or deformed shaft may be expeditiously removed without boring, and with a minimum amount of dismantling of the press.

Other and further objects of my invention will appear from the following description.

In the accompanying drawings which form part of the instant specification and which are to be read in conjunction therewith, and in which like reference numerals are used to indicate like parts in the various views:

Figure 1 is a sectional elevation of a portion of a power press showing the eccentric shaft and eccentric gear containing one embodiment of my invention.

2. Figure 2 is a sectional view taken on the line 2—2 of Figure 1.

Figure 3 is a sectional view similar to Figure 1 with the eccentric at the bottom of the stroke showing the position of parts in the process of being dismantled to free a bent shaft.

Figure 4 is a sectional view taken on the line 4—4 of Figure 3.

In a power press, the eccentric gear rotates at the slowest speed of any rotating part of the press, usually being driven through a gear train from a prime mover. The gear concentric with a shaft meshes with a driving pinion which rotates the gear. Formed integrally with the gear, there is an eccentric which drives a pitman carried thereby.

In general, my invention contemplates the provision of a bearing bushing for the eccentric gear housed in the eccentric hub journal provided with a removable cap. The end bearings for the shaft which support the eccentric gear are formed with removable bushings designed to provide clearance for the removal of the eccentric shaft when it is in deformed or bent condition.

More particularly, referring now to the drawings, the power press frame 6 may be of any suitable construction and carries a pair of lateral bearings 8, one of which is shown in Figure 2. The eccentric shaft 10 is carried in a bearing bushing 12 housed by the bearing 8. It will be observed that the bushing 12 is formed with a flange 14 and that a portion 16 is provided of reduced external cross-sectional dimension. Bearing 8 is formed with a portion 18 of smaller internal dimension so that when the bushing 12 is in position within bearing 8, a space 20 is formed intermediate the ends of the bushing. A cover plate 22 is secured by bolts 24 to the bearing 8.

The eccentric 26, per se, is mounted on the shaft 10 to rotate upon split bushing 28. The eccentric gear is formed with gear teeth 30 adapted to mesh with teeth 32 formed on pinion 34 driven in any suitable manner, as is well known to the art. The eccentric gear is formed with a hub 36, the lower end of which is closed by a cap 38 releasably held in place by a plurality of bolts 40. The pitman 42 is provided with a cap 44 secured to the pitman proper by bolts 46 and forms an eccentric strap. A pitman bearing bushing 48 surrounds the eccentric as can readily be seen by reference to Figure 2. The lower end of the pitman is rockably connected to a slide 50 as is well known to the art.

In the construction shown, pinion 34 will drive eccentric gear 30 to rotate the eccentric 26 thus reciprocating pitman and its associated slides.

Oil deposited in cup 52 will flow through the opening 54, lubricating eccentric sleeve 48. Oil flowing through opening 56 will lubricate the gear bearing bushing 28. Shaft 10 is normally held stationary by means of the keys 58 formed in the cap plate 22 secured to the bearing 8.

If the ram adjustment, which governs the lower limit of the throw of the ram actuated by the pitman, becomes deranged or if more than one press blank is accidentally placed between the dies associated with the ram and thus permit metal to metal contact at the bottom of the stroke at the position of greatest thrust, the tremendous stress set up will easily bend the eccentric gear shaft 10, thus freezing it and immobilizing the press. In the prior art, the eccentric formed integrally with its gear 30 has been of unitary form with a suitable journal bearing for the shaft 10. In this construction, when the shaft becomes deformed, it is necessary to completely dismantle the press and to drill and bore the bent shaft 10 from the press in order to enable its removal. This was an expensive and time-consuming task. With the press equipped with my invention, the deformed shaft may be easily removed.

Referring now to Figures 3 and 4, let us assume that shaft 10 has been bent as shown in Figure 4, and that the press is immobilized. The bolts 46 which secure the pitman cap 44 to the pitman 42 are unscrewed and the pitman cap removed from the press. The bolts 40 which hold the eccentric gear cap 38 to the eccentric 26 are removed permitting the eccentric cap 38 to be removed. This operation may sometimes be difficult due to the deformation of the shaft 10. I provide internally tapped holes 41 for use with jack screws to assist in lifting the eccentric cap 38 from the eccentric gear. When the cap 38 is removed, the eccentric gear which is associated with the eccentric may then be dropped free of the deformed shaft. The ram adjustment may be operated to permit the pitman to move downwardly to allow sufficient clearance to admit dropping the gear.

The bolts 24 holding the cover plate 22 to the stationary lateral bearings 8 are then removed. The threaded openings formerly occupied by the bolts 24 permit the use of jack screws, enabling the sleeve 12 to be pulled to the right as viewed in Figures 2 and 4. As soon as the sleeve 12 moves sufficiently to the right to enter the space 20, it may be easily removed due to the additional clearance provided thereby. When the sleeve 12 is removed, there is ample clearance to remove the deformed shaft which has been freed from the eccentric by means of my removable eccentric cap and the removal of the bearing bushing 12 provides clearance through which the deformed shaft may be conveniently removed without the necessity of boring it, and thus permits me to save time and expense.

It will be seen that I have accomplished the objects of my invention. I have provided an eccentric gear cap for power presses which may be readily and conveniently dismantled to permit the removal of a bent shaft without time-consuming boring and burning operations and without destroying additional press parts. I have provided a new and improved power press eccentric gear cap which will enable me to remove

in a convenient manner a bent and deformed eccentric gear shaft.

It will be understood that certain features and sub-combinations are of utility and may be employed without reference to other features and sub-combinations. This is contemplated by and is within the scope of my claims. It is further obvious that various changes may be made in details within the scope of my claims without departing from the spirit of my invention. It is, therefore, to be understood that my invention is not to be limited to the specific details shown and described.

Having thus described my invention, what I claim is:

1. A power press including in combination a shaft, an eccentric mounted on said shaft for rotation therearound, a pitman adapted to be reciprocated by said eccentric, a unitary gear wheel formed integrally with said eccentric adapted to be driven to rotate said eccentric, said eccentric being formed with a removable cap, means for releasably securing said cap to said eccentric, said pitman having a part surrounding said eccentric and forming an eccentric strap, said eccentric strap being formed with a removable section, means for releasably securing said removable strap section to said pitman, a bearing for said shaft, a removable bushing carried by said bearing, means for securing said bushing to said bearing and means for preventing relative rotation between said shaft and said bearing.

2. A power press including in combination a shaft, an eccentric mounted on said shaft for rotation therearound, a pitman adapted to be reciprocated by said eccentric, a gear wheel formed integrally with said eccentric adapted to be driven to rotate said eccentric, said eccentric being formed with a removable cap, means for releasably securing said cap to said eccentric, said pitman having a part surrounding said eccentric and forming an eccentric strap, said eccentric strap being formed with a removable section, means for releasably securing said removable strap section to said pitman, a bearing for said shaft, a removable bushing carried by said bearing, means for securing said bushing to said bearing, said bearing being formed with an internal portion of enlarged cross-sectional area, said bushing being formed with an external portion of reduced cross-sectional area whereby to provide clearance after a predetermined lateral displacement between said bearing and said bushing, the construction being such that upon removal of said bushing and the removal of said eccentric cap a deformed shaft may be readily removed through said bearing.

3. A power press including in combination a shaft, an eccentric mounted on said shaft for rotation therearound, a pitman adapted to be reciprocated by said eccentric, a unitary gear wheel formed integrally with said eccentric adapted to be driven to rotate said eccentric, said eccentric being formed with a removable cap, means for releasably securing said cap to said eccentric, said pitman having a part surrounding said eccentric and forming an eccentric strap, said eccentric strap being formed with a removable section, means for releasably securing said removable strap section to said pitman, a bearing for said shaft, a removable bushing carried by said bearing, means for securing said bushing to said bearing, said means for securing said bushing to said bearing comprising a plurality of bolts the said bushing being formed with internally threaded

openings and construction being such that upon removal of said bolts jack screws may be inserted into the internally threaded openings to enable the removal of said bushing upon the deformation of said shaft.

VASIL GEORGEFF.
